A. L. SEGELHORST,
MULTIPLE BIT UNDERREAMER,
APPLICATION FILED MAR. 28, 1921.

1,397,114.

Patented Nov. 15, 1921.

UNITED STATES PATENT OFFICE.

AUGUST L. SEGELHORST, OF WHITTIER, CALIFORNIA.

MULTIPLE-BIT UNDERREAMER.

1,397,114.

Specification of Letters Patent. Patented Nov. 15, 1921.

Application filed March 28, 1921. Serial No. 456,364.

To all whom it may concern:

Be it known that I, AUGUST L. SEGELHORST, a citizen of the United States, residing at Whittier, county of Los Angeles, 5 State of California, have invented a new and useful Multiple-Bit Underreamer, of which the following is a specification.

My invention relates to underreamers, being more particularly an underreamer having two or more cutting lugs or jaws.

The principal object of my invention is to produce an underreamer of the class described of strong and durable construction which may be readily assembled and which 15 is efficient in operation.

Other objects and advantages will appear hereinafter from the following specification and drawings.

Referring to the drawings which are for 20 illustrative purposes only,

Figure 1 is a vertical sectional view of one form of my invention, the jaws being shown in collapsed position.

Fig. 2 is a figure similar to Fig. 1, showing the jaws in expanded position.

Fig. 3 is a sectional plan view on line 3—3, Fig. 2.

Fig. 4 is a sectional plan view on line 4—4, Fig. 1.

Fig. 5 is an inverted plan view of the 30 reamer body.

Fig. 6 is a perspective view of the center block, and

Fig. 7 is a perspective view of the spider.

The underreamer consists of a body 11 having a central bore 12 which terminates at its lower end in a shoulder 13 formed at the upper end of a tapered recess 14, such tapered recess also being provided with an 40 intermediate shoulder 15, as is clearly shown in Figs. 1 and 2.

18 designates a center block provided with a flange 19 which engages the shoulder 15 in the recess 14, such center block being tapered 45 above the flange and fitting the walls of the recess above such flange. The lower end of the center block is substantially square in cross section and is provided with upper and lower beveled faces 20 and 21 for the 50 purposes hereinafter described.

The center block is hollow to receive a mandrel 22 and is also provided with radially extending slots 24 through which extend

arms 25 which support the jaws indicated at 26, such jaws being provided with shanks 55 27 which are provided, in turn, with openings 28 to receive the arms 25.

It is understood that the mandrel is inserted in the center block from the top of the same, the arms 25 being received by the 60 slots 24. For the purpose of filling such slots after the mandrel is in place, I provide a spider 30 provided with a head 31 and downwardly extending legs 32, there being a leg 32 for each slot 24. The head of the 65 spider rests upon the upper end of the center block and the legs 32 extend downwardly filling the slots 24 in the center block. The head 31 of the spider engages against the shoulder 13 in the underreamer body and 70 receives the lower end of a coiled spring 33 on the mandrel 22, the upper end of such spring engaging suitable nuts 34 on the upper end of the mandrel.

It will be understood that the mandrel is 75 slideable vertically through the head 31 of the spider and in the center block.

The center block below the flange 19 is shaped to receive the shanks 27 of the jaws 26, such shanks being provided with beveled 80 faces 38 which engage the beveled faces 20 and 21 of the center block when the jaws are in expanded and collapsed positions respectively.

The recess in the lower end of the mandrel 85 is formed with vertical extending ways 40 which receive the shanks of the cutting jaws, as shown in Fig. 3, the center block being substantially circular in form with flat faces 42 formed thereon and the recess in the 90 body of the underreamer being similarly formed to receive the center block. This shaping of the center block is for the purpose of having a center block of maximum size without cutting down the size of the 95 shanks of the jaws thereby giving the jaws maximum strength.

The center block and spider are held in the body of the underreamer by means of U-shaped bolts 45, clearly shown in Fig. 4, such 100 bolts extending through the body and engaging the center block and legs of the spider, as shown in Figs. 1, 2 and 4, suitable nuts being provided for the bolts, as indicated at 46.

In the form shown, the cutting jaws are

substantially flat in cross section and it is understood that two or more jaws may be used.

The operation of the parts is clearly shown in Figs. 1 and 2.

In Fig. 1 the mandrel is shown pulled downwardly from the body which allows the jaws to collapse into the position shown in Fig. 1, the jaws being cut away on their inner face as shown at 50 so that the same will clear the lower end of the center block and allow the jaws to collapse into the position shown.

In Fig. 2 the mandrel has moved into its upper position due to the action of the spring 33, the jaws being moved upwardly until the upper ends of the shanks and jaws engage the flange 19 on the center block, the beveled faces 38 on the jaws coming into contact with the beveled faces 20 on the center block and the upper ends of the shanks above such beveled faces 38 fitting against the sides of the center block, as shown in Fig. 2, such construction providing a firm connection between the body of the underreamer and the jaws.

Shoulders 52 are also provided on the jaws which engage the lower edge of the underreamer body as shown in Fig. 2.

30 I claim as my invention:

1. In an underreamer; a body having a tapered recess extending into the lower end thereof; a circular shoulder in said recess; a center block extending into said recess having a central bore and slots extending radially therefrom; a flange on said center block engaging said shoulder; bolts in said body engaging said center block; a mandrel slidably mounted in said body, radially extending arms on the lower end of said mandrel; a plurality of cutting lugs; shanks on said lugs extending into said recess and each having an arm receiving opening therein; a spider on the upper end of said center block; legs on said spider extending into the slots in said center block; a coiled spring on said mandrel above said spider; and means on said mandrel for confining said spring.

50 2. In an underreamer; a body having a tapered recess extending into the lower end thereof; a center block extending into said recess having a central bore and slots extending radially therefrom; means for securing said center block in said body; a mandrel slidably mounted in said body;

arms on the lower end of said mandrel extending outwardly through the radial slots in the center block; a spider on the upper end of said center block; legs on said spider extending into the slots in the center block above the arms on said mandrel; a plurality of cutting lugs, shanks on said lugs extending into said recess in the lower end of the body; and elastic means for pulling said mandrel upwardly.

3. In an underreamer; a body having a recess extending into its lower end; a center block in said recess; means for securing said center block in said body; said center block having a central bore and slots extending outwardly through the slots in said center block; a spider; a head on said spider seated on the upper end of said center block; legs on said spider extending downwardly into the slots in said center block; a plurality of cutting lugs having openings to receive the arms on the mandrel; and means for elastically supporting said mandrel.

4. In an underreamer; a body having a recess extending into the lower end thereof and a central bore; a shoulder at the upper end of the recess; an intermediate shoulder formed in said recess; a center block in said recess having a central bore and a plurality of slots extending radially therefrom; a flange on said center block engaging the intermediate shoulder in said recess; means for securing said center block in said recess; a mandrel slidably mounted in said center block; arms on said mandrel extending through the slots in the center block; a plurality of cutting lugs engaging said arms; a coiled spring on said mandrel above the center block and nuts on said mandrel engaging the upper end of said spring.

5. In an underreamer; a body; a center block in said body having radially extending slots extending downwardly from the upper end thereof and a central opening to receive a mandrel; a mandrel; radially extending arms on the lower end of said mandrel, said arms extending through the slots in said center block; means for filling said slots above said arms; cutting lugs mounted on said arms; and means for placing an elastic tension on said mandrel.

In testimony whereof, I have hereunto set my hand at Los Angeles, California, this 22nd day of March, 1921.

AUGUST L. SEGELHORST.
